Inventor:

Reginald C. Clinker;

by Alexander S. Kent,
His Attorney.

UNITED STATES PATENT OFFICE.

REGINALD CHARLES CLINKER, OF BILTON, NEAR RUGBY, ENGLAND, ASSIGNOR TO
GENERAL ELECTRIC COMPANY, A CORPORATION OF NEW YORK.

ANTENNA.

Application filed February 13, 1924, Serial No. 692,463, and in Great Britain February 28, 1923.

My present invention relates to a wireless signalling aerial or antenna and more particularly to an aerial of the frame or loop type.

- 5 In accordance with the present invention the frame aerial is made collapsible and consists of a number of radial arms, which are adapted to support the aerial wire, pivotally attached to a central boss or base plate.
10 The aerial is preferably so constructed that when it is opened out the arms move slightly beyond the position in which they are in one plane and are so arranged that in the extended position they are kept rigid and
15 locked to the base plate by the tension in the wire. Thus when not in use the frame antenna can be folded up and is compact and readily portable.

The invention is illustrated in the accompanying drawings in which Figure 1 is an elevation of the aerial in its extended position; Figure 2 is an enlarged view of the boss, showing how the radial arms are attached thereto; Figure 3 is a side elevation of Figure 2; and Figure 4 is a view showing the manner in which the frame may be secured to a collapsible support.

As shown in Figure 1, the aerial consists of four arms 10, 11, 12 and 13 which are attached to a central boss or base plate 14 by pivots which are spaced from the stop surface of the base plate, the latter constituting a holding member. The arms radiate from the base plate and form with the plate a toggle joint for locking the arms in the normal expanded position. The aerial wire 15 is wound upon these four arms in the form of a square spiral, the wire being located in slots cut in the radial arms and held in position in the slots by means of retaining members 16 which are attached to the arms so as to cover the open ends of the slots. These slots may be positioned an equal distance from one another or they may be so spaced that the length of each complete turn of wire bears a particular relation to the length of the adjacent turns.

The arm 10 is provided with a number of terminals 17, a corresponding number of turns of the wire being in conducting relation with a terminal. The terminals are in the form of plugs and any two terminals may be connected together by means of the plug connectors 18 so as to short-circuit any given number of turns of the wire.

In Figure 3, it will be noticed that on extending the arms they move slightly beyond the position in which they are in one plane and the tension of the wire thus serves to lock the arms to the base plate and to keep 60 the frame rigidly extended. Similar reference numerals are used in each figure to refer to like parts.

On swinging the arms together around their respective pivots, the wire falls in 65 the natural folds and shows no tendency to get entangled. A suitable stand may be provided on to which one of the arms may be fixed, this arm then being preferably of greater length than the remaining arms. 70 This stand may be of tripod form, as indicated in Fig. 4, the legs 19 of the tripod being adapted to fold onto the arm 10 to which the tripod head 20 is attached. The legs of the tripod are attached to the head by 75 means of pins 21 which are free to slide in the slots 22. The weight of the frame on the head forces the pins to the end of the slots so that the upper ends of the tripod legs bear against the arm 10 of the frame 80 as indicated, thus keeping the tripod rigid. When the frame is lifted the legs may be rotated around the pins and closed together for transportation.

What I claim as new and desire to secure 85 by Letters Patent of the United States, is,—

1. A collapsible frame antenna comprising a central boss, a plurality of radial arms pivotally attached to said boss, and a plurality of turns of wire secured to said arms, 90 said arms being so arranged that when extended they will move a small distance beyond the position where they are all in one plane and will be held in position by the tension of the wire.

2. A collapsible frame antenna comprising a central boss, a plurality of radial arms pivotally attached to said boss at opposite points thereof and adapted to fold together and a support for said antenna comprising 100 a plurality of legs attached to one of said arms near the end remote from said boss in such a way that the legs may be folded together.

3. A collapsible frame antenna comprising a central boss, a plurality of radial arms pivotally attached to said boss and adapted to fold together and a support for said antenna comprising a plurality of legs attached to one of said arms by a pin and 110

slot connection in such a way that the weight of the frame will force the pins to the ends of the slots thereby causing the upper ends of the legs to bear against the frame arm 5 and hold the legs in their extended position.

4. A loop antenna frame construction which comprises a plate, a plurality of antenna supporting arms radiating from said plate and pivoted thereto, and means on the 10 arms adapted to automatically lock the arms to the plate when the arms are moved to normal expanded position.

5. A loop antenna frame construction, which comprises a plate, a plurality of antenna supporting arms radiating from said 15 plate and pivoted thereto, and spring means on the arms adapted to automatically lock the arms to the plate when the arms are moved to normal expanded position.

6. In a foldable antenna loop holder, a holding member having a stop surface, a plurality of pivots on said member, said pivots spaced apart from said stop surface, a plurality of arms mounted to swing upon 25 said pivots, a loop on said arms said loop lying in a plane beyond the plane of the pivots and towards the plane of the stop surface whereby said arms are tensioned against said stop surface when in open 30 position.

7. A portable antenna loop holder and support, comprising a base plate having a stop surface, a loop, and loop supporting arms, said arms radiating from said plate and hinged thereto at spaced points to form with said plate a toggle joint for locking the arms in open position.

8. In an antenna loop, radiating arms breakable at the centre to fold upon each other, a loop on said arms and a toggle connection including a base plate and spaced

pivots for tensioning the loop and locking the arms in open position.

9. In an antenna loop, radiating arms breakable at the centre to fold upon each 45 other, a loop on said arms and a base plate or toggle joint member on which said arms open and are locked in open position.

10. A collapsible radio receiving loop comprising a frame having vertical and 50 horizontal arms in hinged relation, to be capable of folding into parallelism, the outer ends of the arms having means for engaging the coiled wire and said arms having means whereby the tension of the strung 55 wire holds them extended for service.

11. A collapsible radio receiving loop comprising a frame having vertical and horizontal arms; a fitting, means for pivoting said arms, at their butt ends, respectively to said fitting, whereby said arms are rendered capable of folding into parallelism; the outer ends of the arms having means for engaging the coiled wire, and said arms having means whereby the tension of the 60 strung wire holds them extended for service.

12. A collapsible radio receiving loop comprising a frame having radial arms arranged in lengthwise pairs, a fitting common to said arms having a stop plate, pivots upon 70 said fitting engaging the butt ends of said arms, said arms provided at their free ends with wire engaging means, offset relatively to the pivots, whereby the tension of the strung wire is exerted in the plane of the 75 chord intersecting the wire engaging means, pressing the arms against the stop plate.

In witness whereof, I have hereunto set my hand this twenty-third day of January, 1924.

R. C. CLINKER.
